UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BLACKING-MACHINE.

1,311,161.

Specification of Letters Patent.

Patented July 29, 1919.

Application filed November 29, 1915. Serial No. 64,025.

To all whom it may concern:

Be it known that I, FREDERICK M. FURBER, a citizen of the United States, residing at Revere, in the county of Suffolk and State 5 of Massachusetts, have invented certain Improvements in Blacking-Machines, of which the following description, in connection with the accompanying drawings, is a specification, like reference characters on the drawings 10 indicating like parts in the several figures.

This invention relates to blacking machines, and particularly to machines such as are used for applying blacking to parts of 15 shoes in the process of shoe manufacture. A particular object of the invention is to provide a machine suitable for use in applying blacking to the margin of a shoe sole before the sole is incorporated in the shoe; but it 20 will be apparent from a consideration of the construction hereinafter described that the invention is not thus restricted in its application and that a machine embodying the novel features of the invention is susceptible 25 of a variety of uses.

In the manufacture of some types of shoes such, for example, as McKay shoes, in which the margin of the upper surface of the sole proper is exposed in the finished shoe, it is 30 the practice to apply blacking to this portion of the sole before the sole is incorporated in the shoe. This operation is performed usually by the use of a brush which is first dipped in the blacking and then applied to the sole, the operator holding the brush in one hand and the sole in the other. It will be readily understood that as thus 35 carried out the operation is slow and the results also are far from uniform, since the width of the margin upon which the blacking is applied is likely to vary and a larger quantity of blacking is likely to be applied to some portions of the surface than to others.

It is an important object of this invention 45 to provide a machine for use in applying blacking to the margins of soles, in order to avoid the necessity of applying the blacking by hand, and thus improve the quality of the

work and increase the amount of work that 50 an operator may perform in a given time. I have found that the blacking may be applied effectually and uniformly to the work if delivered in the form of spray; and means for effecting such delivery of the blacking together with means for determining the position of the work to cause the blacking to be applied effectually to that portion of the work which it is desired to black, present important features of the invention.

A further feature of the invention consists in a novel construction and arrangement of means for effecting a delivery of blacking in such manner as to permit a portion of the blacking to be applied to the work and 60 means for recovering the unutilized portion 65 of the blacking. The construction herein shown comprises a blacking receptacle and means for drawing blacking from the receptacle and delivering it in the form of spray in such manner that the unutilized portion of the blacking in the spray is returned to the receptacle. In this construction the blacking receptacle is partially open 70 at the top and the spray is directed toward 75 the opening. I have found that the surplus spray is received within the receptacle much more readily and effectually, without the liability that vapor from the spray may be dispersed in the surrounding air before it reaches the opening, if the machine is provided with means for facilitating the inward 80 flow of air and spray at the opening, and the provision of such means constitutes a further feature of the invention.

Still another feature of the invention resides in a novel construction and arrangement of means for spraying the blacking and for varying the consistency of the spray to meet the requirements of varying conditions of use. This means may advantageously be combined with means for adjustably positioning the work to correspond with the variations in the consistency of the spray.

The above and other features of the invention, including certain details of construction and combinations of parts, will now be

described with reference to the accompanying drawings and pointed out in the claims.

In the drawings,

Figure 1 is a view in side elevation, with portions shown in section, of a machine in which the invention is embodied,

Fig. 2 is a section on the line 2—2 of Fig. 1,

Fig. 3 is an enlarged sectional view showing in greater detail a portion of the mechanism shown in Fig. 1, and

Fig. 4 shows in front elevation a portion of the mechanism illustrated in Fig. 3.

Mounted upon a standard 2 is a casting 4 which is formed to provide a reservoir 6 for compressed air and has means for supporting a receptacle 8 for blacking, this means comprising a lug 10 on the casting from which project forwardly a pair of pins 12, only one of which is seen in the drawings. The receptacle 8 has a depending lug 14 suitably bored to receive the pins 12 and permit the receptacle to slide on the pins into the position shown in the drawings. The receptacle 8 is formed on its rear side to provide an outlet conduit 16, the purpose of which will be subsequently explained, and this conduit fits within the flanged end of a conduit 18 secured to the side of the air reservoir 6, the conduit 18 thus affording additional support for the blacking receptacle. A thumb screw 20 threaded in the conduit 16 and engaging the conduit 18 serves to clamp the conduit 16 in position within the conduit 18 and thus to prevent the receptacle 8 from slipping forwardly on the pins 12.

Air is forced into the reservoir 6 by means of a pump comprising a cylinder 22 bolted to the side of the reservoir and communicating therewith, as shown by dotted lines in Fig. 1, and a piston 24 within the cylinder driven by means of a pitman 26 from a crank on a shaft 28 which is supported in bearings on a bracket 30 projecting upwardly from the reservoir casting 6. The specific details of construction of the pump are not shown herein since they form no part of the present invention. The shaft 50 is arranged to be driven from a suitable source of power through a pulley 32 which is secured thereon. A loose pulley 34 also is mounted on the shaft, and the starting and stopping of the pump are to be controlled by means of a belt shifter 36 which may be of the same form as that disclosed in my prior patent No. 1,136,116, granted April 30, 1915.

The reservoir 6 is provided with an outlet 38, and bolted to the reservoir is a conduit 40 in which is a passage 42 that communicates with the outlet 38. This passage leads to a lateral outlet 44 formed in a cylindrical boss 46, upon which is mounted to turn in a

vertical plane a conduit 48 having a passage 50 that communicates through an opening 52 with the outlet 44. A leather washer 54 serves to prevent escape of air at the joint between the two conduits 40 and 48. In order to keep the joint tight and to assist in supporting the conduit 48, a spindle 56 is threaded through a projection 58 on this conduit at the axis of its turning movement and has a pointed end to engage in a bearing in the side of the conduit 40. The purpose of the arrangement whereby the conduit 48 is permitted to turn about the bearing 46 will be subsequently explained.

The air conduit 48 supports at its outer end a blacking supply conduit comprising a pipe 60 arranged to extend vertically downward into the blacking in the receptacle 8 and having a vertical passage 62 which communicates with a horizontal passage 64 in a head 66 on the pipe. Opening downwardly from the bottom of the passage 64 is an outlet 68. Extending upward from the head 66 in laterally offset relation to the pipe 60 is a cylindrical projection 69 which fits within a vertical transverse opening in the conduit 48, so that the position of the pipe 60 may be varied by turning the member 69, and this member is provided centrally with a vertical bore 70 in line with the outlet 68 and communicating through an opening 72 with the passage 50 in the conduit 48. The conduit 48 is formed to provide an annular passage 74 extending around the member 69 so that the opening 72 may communicate with the passage 50 in all positions of adjustment of the member 69. This member is retained in adjusted position by means of a nut 76 threaded upon its upper end, suitable washers 78 and 80 being provided between the conduit 48 and the head 66 and the nut 76 respectively so as to prevent escape of air at the joints.

Within the bore 70 is threaded a nozzle member 82 having passages suitably formed to receive air from the opening 72 and direct the air in a fine stream through a nozzle 84 which is arranged to project partly across the passage 64 in line with the center of the outlet 68, the opening in the nozzle being smaller in diameter than the outlet 68. With the parts thus arranged the stream of air issuing from the nozzle 84 will cause blacking to be drawn up from the receptacle through the passages 62 and 64, atomized at the outlet 68, and delivered downwardly in the form of spray. The work to which blacking is to be applied, as illustrated by the sole 61 shown in Fig. 1, is presented below the outlet 68 in the path of the spray, and the pipe 60, which is substantially parallel to the line of delivery of the spray, is arranged, in the construction shown, to serve as means to determine the position of the

work. Such means is of particular utility in case it is desired to apply blacking to a portion only of the work, as in blacking the margin of a sole. For this purpose the sole 5 will be positioned in a horizontal plane with its edge in contact with the pipe 60 and will be moved to draw the margin through the spray. In order that the width of the blacked margin may be uniform, the sole should 10 be moved with its edge continuously in engagement with the pipe at substantially the same point. For the best results the sole should engage the pipe at a point directly opposite to the line of delivery of the spray 15 so that the outlet 68 may be directly over that portion of the work which is to be blacked. In the drawings the pipe 60 is shown as positioned in a vertical plane extending directly rearward from the front 20 of the machine through the outlet 68, and the sole would be moved across the front of the pipe from right to left or from left to right at the convenience of the operator. It frequently happens, however, that the machine 25 is so positioned with reference to the source of light, or the position of the rack from which the soles are taken is such, that it is more convenient to move the soles through the path of the spray diagonally 30 with reference to the plane above mentioned. For this purpose the pipe 60 should be positioned somewhat at one side or the other of said plane so as to present the guiding surface for the edge of the sole in a different 35 direction from the axis of the outlet 68 and not directly at the rear of said axis. The pipe 60 may be thus adjusted to suit the convenience of the operator by turning the offset member 69 within its bearing in the outer 40 end of the air conduit 48, as hereinbefore explained.

In order that the machine may operate in an effective manner, it is important that the work be presented at the proper distance 45 from the outlet 68. The velocity of the air jet is of course, greater near the outlet than it is at a distance from the outlet and decreases as the distance from the outlet increases. If the work is presented too near 50 the outlet where the velocity is high, it will cause the spray to be deflected laterally to such an extent that some of the vapor will be dispersed in the surrounding air and all of the surplus blacking will not be returned 55 as it should to the receptacle. Another condition to be considered is that near the outlet the blacking is more finely atomized than it is at a distance from the outlet, where it tends to condense and form particles of 60 larger size. In operating upon a comparatively smooth surface such as is presented by the grain side of leather the particles of blacking, if too large, will tend to spatter and thus to stain a portion of the work

which it is not desired to black, while particles of such size would be readily absorbed upon striking a rougher surface such as presented by the flesh side of leather, for example, on the upper side of a turn shoe sole. In order to indicate the proper distance 65 from the outlet at which the work should be presented, the machine is provided with a gage 86 secured by means of a screw 88 to the front of the head 66, and in operation the sole will be presented with 70 its upper surface in engagement with the lower end of the gage while its edge engages the pipe 60. The gage is provided moreover with a slot 90 which permits it to be adjusted vertically relatively to the screw 88 75 to meet different conditions as to the character of the surface to be blacked or the velocity of the current. By experienced operators the gage 86, as far as its function of determining the distance from the outlet at 80 85 which the sole should be positioned is concerned, may conceivably be dispensed with, but even in the case of such operators the use of the gage will be found preferable for the best results. The sole engaging surface 90 of the gage is indicated at 86^b, Fig. 3.

The gage 86, in the construction shown, comprises a plate which extends laterally as shown in Fig. 4, and as thus constructed the gage, through its surface 86^a, has the additional function of protecting from contact with the spray portions of the work which it is not desired to black. The width of the margin to which blacking is applied will thus substantially equal the distance between 100 the gage and the pipe 60, and the shape of the gage may be variously modified to vary the width of this margin. Since the gage is secured to the front of the head 66, it will sustain a fixed relation to the pipe 60 for 105 all positions of adjustment of the pipe, and will thus extend at all times in parallel relation to the path of movement of the margin of the sole, as the margin is moved longitudinally across the path of the spray, and 110 thus limit the width of the blacked margin and avoid waste of the blacking.

In addition to the provision for adjustment of the gage 86, whereby the position of the work may be controlled, to some extent, 115 with reference to the size of the particles of blacking in the spray, the construction hereinbefore described provides means for varying the consistency of the spray. The size of the particles in the spray, other conditions being equal, will vary in accordance with the thickness of the blacking, and this will depend somewhat upon the temperature of the surrounding atmosphere. Means for controlling the consistency of the spray is 120 afforded by the provision for adjustment of the member 82, whereby the member may be turned to position the end of the nozzle

84 at different distances from the outlet 68. If a finer spray is desired, the member 82 should be turned to position the nozzle nearer to the outlet, and if the nozzle is 5 moved in the opposite direction the result will be to increase the size of the particles of blacking in the spray. By adjusting the nozzle the machine may be quickly adapted to small variations in operating conditions 10 without the necessity of changing the position of the guide 86.

Secured to the lower end of the pipe 60 is a strainer 92 provided with a large number of small openings in its top and bottom 15 to admit the blacking, the purpose of the strainer being to prevent the admission to the pipe 60 of foreign matter or fluid of such thickness as would tend to clog the supply passages. As previously explained, 20 the conduit 48 which supports the pipe 60 and the strainer 92, is mounted to turn in a vertical plane upon the bearing 46, which permits the pipe and the strainer to be raised above the blacking when the machine 25 is not in use. The conduit 48 carries a spring plunger 94 which is arranged to enter an opening 96 in the casting 40 to support the conduit, the pipe and the strainer in operative position, as shown in 30 Fig. 1. Another opening 98 is provided in the casting 40, and when the conduit 48 is to be swung upward to withdraw the pipe and the strainer from the blacking, the plunger 94 is withdrawn from the opening 35 96 by pulling upon a knob 100 connected with the plunger, and the latter is then caused to enter the opening 98 to support the parts in upraised position as indicated by dotted lines in Fig. 1. As thus supported 40 the pipe 60 and the head 66 will be inclined so as to permit the blacking to drain from the normally horizontal passage 64 and thus prevent the blacking from drying within and clogging the passage.

45 In order to prevent excessive pressure in the reservoir 6 and thus to regulate the velocity of the current of air issuing from the nozzle 84, the machine is provided with a relief valve 102 having a rounded lower 50 end seated over an opening 104 that communicates through the top of the conduit 40 with the air passage 42, the valve being mounted loosely within a vertical bore formed in a projection 106 on the conduit 55 and maintained normally by its own weight in position to close the opening 104. In the event of excessive pressure within the reservoir 6 and the air conduit, the valve 102 is raised and the excess of air escapes past the 60 valve and through the openings 108.

Whatever may be the consistency of the principal portion of the spray that issues from the outlet 68, the spray will be found to contain more or less vapor comprising 5 very minute particles of blacking which tend

to float away in the surrounding air and to dry rapidly so as to form particles in the nature of soot which may be inhaled by the operator. In order to protect the operator from this annoyance and possible danger to 70 health, the machine is constructed to insure the immediate return to the receptacle of all the unutilized blacking, including such vapor, and the recovery of substantially all the surplus blacking for subsequent use. To 75 this end the receptacle 8 is provided at its top with a downwardly inclined rim 110 which partially closes the receptacle but leaves a central opening of sufficient width to admit the surplus spray, as well as to 80 permit the pipe 60 and the strainer 92 to be raised from the receptacle through the swinging of the conduit 48. The outlet conduit 16 previously referred to opens into the receptacle beneath the rim 110 and above the 85 surface of the blacking and thus affords an outlet communicating with the conduit 18 which is in the form of a T with a vertically bored head portion 112 at its outer end. Closing the lower end of the passage in the 90 head 112 is a cap 114 into which are threaded screws 116 that are received within slots in the head and serve to clamp the cap in place. Extending through the cap 114 is a pipe 118 provided with a restricted opening 120 at its 95 upper end, this pipe communicating with the air reservoir 6 through a flexible tube 122 and a pipe 124. Secured to the upper end of the head 112 by means of screws 126 is an outlet pipe 128. With the parts thus 100 constructed and arranged, a jet of air will be delivered continuously from the opening 120 while the machine is in operation, and this will induce an outward current through the conduits 16 and 18 and thence through 105 the pipe 128. The passage of the surplus spray through the opening in the top of the receptacle is facilitated by the provision of the relief outlet 16, and in the construction illustrated the effect is enhanced by the positive induction of an inward current of air and spray through the opening in the receptacle by reason of the arrangement of the air jet issuing from the opening 120. Insurance is thereby afforded that vapor comprising the finer particles of blacking in the spray will not be dispersed in the surrounding air but will be received within the receptacle 8 where substantially all the blacking 115 will be condensed. The pipe 128 may lead 120 to any desired point, but any vapor finally issuing from this pipe will be so small in quantity as to be negligible. The arrangement of slots in the head 112 permits the pipe 128 to be secured, if found more convenient, to the lower end of the head and the cap 114 in the upper end, a flexible connection 122 of suitable length for this purpose being provided.

In the operation of the machine the air 130

pump, it will be understood, is driven continuously to maintain the requisite pressure in the reservoir 6, and the maximum pressure is limited by the relief valve 102. Jets 5 of air are thus delivered continuously from the outlets 84 and 120, the jet issuing from the nozzle 84 creating suction to cause blacking from the receptacle 8 to flow through the passages 62 and 64 to the outlet 68 where 10 it is atomized by the air jet and delivered downwardly in the form of spray. The sole or like article to the margin of which blacking is to be applied is presented with its edge in contact with the pipe 60 at a distance 15 from the outlet indicated by the gage 86 and is moved to draw its margin through the spray, the pipe 60 having been previously adjusted by turning the member 69 within the opening in the conduit 48 so as to position 20 the pipe in the proper relation to the outlet 68 to suit the convenience of the operator. The surplus blacking in the spray is returned to the receptacle 8 through the opening in its top, such return being facilitated 25 by the inward current at the opening induced by the operation of the air jet 120.

When it is desired to stop the operation of the machine, the belt is transferred by means of the belt shifter 36 to the loose 30 pulley 34 and the pump then ceases to force air into the reservoir 6. The plunger 94 may then be withdrawn from the opening 96 and the conduit 48 swung upward to raise the pipe 60 and the strainer 92 from 35 the blacking, the plunger 94 then engaging in the opening 98 to support the parts in upraised position and permit the blacking to drain from the passages 62 and 64.

It will be apparent that there is nothing 40 in the construction shown and described to restrict the machine to the use of fluid of any particular character, and it should be understood that the term "blacking" as used herein is not restrictive but is to be given a 45 broad interpretation consistent with applicant's intention to claim all the protection to which he is entitled for the various novel features of the invention.

Having described the invention, what I 50 claim as new and desire to secure by Letters Patent of the United States is:

1. A machine of the class described having, in combination, means for delivering blacking in the form of spray, and means for 55 variably determining the relative position of the margin of a shoe sole with respect to the diverging path of said spray, the last mentioned means operating also to cause the blacking to be applied along a predetermined portion of the margin of the sole.

2. A machine of the class described having, in combination, means for delivering blacking in the form of spray, and a work 60 guide having a uniform surface extending 65 in the general direction of the path of the

spray to aid the operator in applying blacking to a definite portion of the work as the work is moved in contact with the guide at any desired distance from the point of delivery of the spray.

3. A machine of the class described having, in combination, means for delivering blacking in the form of spray, and a member 70 extending into the path of the spray and arranged to act as a guide for the edge of a shoe sole as the sole is moved lengthwise of said edge to cause the blacking to be applied along the margin of the sole.

4. A machine of the class described having, in combination, means for delivering 75 blacking in the form of spray, and means arranged in a definite relation to the line of delivery of said spray, said means being constructed to provide a plurality of guiding surfaces variably distant from the point of 80 delivery of the spray adapted for association with the work to thereby determine the relation of the work with regard to the point of delivery and the line of delivery of the spray.

5. A machine of the class described having, in combination, means for delivering blacking in the form of spray, and a work 85 guide extending longitudinally of the path of the spray to permit the work to be positioned in the path of the spray at different 90 distances from the point of delivery.

6. A machine of the class described having, in combination, means for delivering blacking in the form of spray, and a work 95 guide extending substantially parallel to the line of delivery of the spray and arranged to engage the edge of a shoe sole to position the margin of the sole in the path of the spray, said guide being formed to permit the 100 sole to be presented at different distances from the point of delivery of the spray.

7. A machine of the class described having, in combination, means for delivering blacking in the form of spray, and adjustable means for variably determining the distance 110 from the point of delivery of the spray at which work shall be presented in the path of the spray.

8. A machine of the class described having, in combination, means for delivering blacking in the form of spray, a work guide 115 extending longitudinally of the path of the spray, and means having a face for determining the position longitudinally of the 120 guide in which the work is to be presented in contact with the guide.

9. A machine of the class described having, in combination, means for delivering blacking in the form of spray, a work guide 125 extending longitudinally of the path of the spray, and a member having a gage surface adjustable longitudinally of the guide for determining the position in which the work is to be presented in contact with the guide. 130

10. A machine of the class described having, in combination, means for delivering blacking in the form of spray, means for engaging the edge of a shoe sole to determine the position of the sole with reference to the line of delivery of the spray, and means having a face for engaging the face of the sole to determine the distance of the sole from the point of delivery of the spray.
11. A machine of the class described having, in combination, means for delivering blacking in the form of spray, means for determining the position of work to cause the margin of the work to be presented in the path of the spray, and means having a face for shielding other portions of the work from the spray.
12. A machine of the class described having, in combination, means for delivering blacking in the form of spray, means at one side of said delivery means for engaging the edge of the work to cause the margin of the work to be positioned in the path of the spray, and means at the other side of said delivery means for engaging the face of the work having a surface arranged to limit the width of the blacked margin.
13. A machine of the class described having, in combination, means for delivering blacking in the form of spray, and means at one side of the path of said spray having a surface for confining the spray to the marginal portion of the work.
14. A machine of the class described having, in combination, means for delivering blacking in the form of spray, a work guide extending longitudinally of the path of said spray at one side of the line of delivery of the spray, and a shield extending longitudinally of said path at the other side of said line of delivery.
15. A machine of the class described having, in combination, means for delivering blacking in the form of spray, a work guide extending longitudinally of the path of said spray at one side of the line of delivery of the spray, and means at the other side of said line of delivery for determining the distance from the point of delivery at which the work is to be presented in the path of the spray, said last named means being constructed and arranged also to shield portions of the work from the spray.
16. A machine of the class described, having, in combination, a support, means carried thereby for delivering blacking in the form of spray, and a work guide positioned with reference to said delivery means to cause the blacking to be applied to a portion of the work presented in contact with the guide, said guide and spray delivery means being adjustable relatively to one another and to the support to permit the guide to be positioned in different directions from the line of delivery of the spray.
17. A machine of the class described having, in combination, a support, means carried thereby for delivering blacking in the form of spray, and a work guide for determining the position of work in the path of the spray, said guide being adjustable angularly about the line of delivery of the spray.
18. A machine of the class described having, in combination, a support, means carried thereby for delivering blacking in the form of spray, and a work guide between the point of delivery of the spray and the support, said guide being adjustable laterally with reference to a vertical plane extending rearwardly through said delivery point and the support.
19. A machine of the class described having, in combination, means for delivering blacking in the form of spray, and a work guide extending longitudinally of the path of the spray, said guide being adjustable about an axis substantially coincident with the line of delivery of the spray.
20. A machine of the class described having, in combination, means for delivering blacking in the form of spray, a guide at one side of the line of delivery of the spray for determining the position of the margin of the work in the path of the spray, and a shield at the other side of said line of delivery for protecting other portions of the work from contact with the spray, said guide and shield being adjustable about the line of delivery of the spray without altering their relation to each other.
21. A machine of the class described having, in combination, an air supply conduit, air delivery means mounted on said conduit, and means for conducting blacking into the path of the air delivered from said means to cause the blacking to be atomized by the air, comprising a pipe depending from said air delivery means in offset relation to the line of the air current, said pipe being arranged to serve as a work guide, and the air delivery means being arranged for turning movement to adjust said guide without interrupting communication between said means and the air conduit.
22. A machine of the class described having, in combination, a receptacle provided with an opening, and means external of the receptacle for delivering blacking in such manner as to cause the unutilized portion of the blacking to enter the receptacle through said opening, said delivery means being so constructed and arranged relatively to the receptacle as to position work to which blacking is to be applied between said means and the receptacle.
23. A machine of the class described having, in combination, a receptacle provided with an opening, means for drawing blacking from said receptacle and discharging it over said opening to permit the unutilized

portion of the blacking to be returned to the receptacle, and means connected to said first mentioned means for determining the position of work to which blacking is to be applied to cause said work to receive a portion of the blacking discharged over the receptacle.

24. A machine of the class described having, in combination, a receptacle for blacking, means for drawing blacking from said receptacle, spraying said blacking and returning the unutilized portion of the blacking to the receptacle, and relatively fixed guiding means for determining the position of work to which blacking is to be applied as it is moved through said spray past said guiding means.

25. A machine of the class described having, in combination, a receptacle for blacking, a pipe extending upward from said receptacle, and means for drawing blacking upward in said pipe and returning it downward outside of the pipe in the form of spray, the pipe being arranged to serve as a guide for work presented in the path of said spray.

26. A machine of the class described having, in combination, a blacking receptacle, a blacking supply conduit extending upward from said receptacle and having a horizontally extending portion at its upper end, said horizontal portion of the conduit having an opening in its lower side, and means for directing a jet of air through said opening to cause the blacking to be sprayed in the direction of the receptacle.

27. A machine of the class described having, in combination, a receptacle for blacking provided with an open top, an air conduit extending over the top edge of said receptacle, a blacking supply conduit extending upward from the receptacle to a point sufficiently removed from the top edge thereof to allow the introduction of work between said conduit and the top edge of the receptacle, and means for delivering a jet of air from the air conduit, said air delivery means being arranged with reference to the blacking supply conduit to cause the blacking to be directed in the form of spray toward the receptacle.

28. A machine of the class described having, in combination, an open receptacle for blacking, an air conduit extending over said receptacle, a blacking supply conduit arranged to be supported by said air conduit and to dip into the blacking in the receptacle, and means for delivering a jet of air from the air conduit in position to atomize the blacking, said air conduit being movable to withdraw the blacking supply conduit from the receptacle.

29. A machine of the class described having, in combination, an open receptacle for blacking, an air conduit extending over said

receptacle, a blacking supply conduit arranged to be supported by said air conduit and to dip into the blacking in the receptacle, said blacking conduit having a horizontally extending portion at its upper end, 70 and means for delivering a jet of air transversely of said horizontal portion of the conduit to atomize the blacking, said air conduit being mounted to swing upwardly to an inclined position so as to permit the 75 blacking to drain from said horizontal portion of the blacking conduit when the machine is not in use.

30. A machine of the class described having, in combination, a blacking receptacle, a compressed air reservoir, an air conduit communicating with the air reservoir and extending over the blacking receptacle, and a blacking supply conduit supported by the air conduit, said air conduit being movable 85 to cause the blacking supply conduit to dip into the blacking in the receptacle or to be withdrawn from the blacking without interrupting the communication between the air conduit and the air reservoir. 90

31. A machine of the class described having, in combination, means for delivering a jet of air, means for conducting blacking into the path of said air jet to cause the blacking to be delivered in the form of 95 spray, said air delivery means and blacking conducting means being relatively adjustable longitudinally of the path of the air jet to vary the size of the particles of blacking in the spray, and means adjustably to position the work in accordance with the variation in the spray. 100

32. A machine of the class described having, in combination, a blacking supply conduit formed with a lateral delivery opening, 105 and an air delivery nozzle arranged to direct a jet of air outwardly through said opening, said conduit being constructed and arranged to serve as a guide for work presented in line with said opening. 110

33. A machine of the class described having, in combination, a blacking receptacle formed with an opening, and means for delivering a spray of blacking in the direction of said opening, the receptacle being provided with a relief outlet above the body of the blacking to facilitate the passage of the spray through said opening. 115

34. A machine of the class described having, in combination, a blacking receptacle 120 formed with an opening in its top, and means for delivering a spray of blacking downwardly toward said opening, the receptacle being provided with a lateral relief outlet above the body of the blacking to 125 facilitate the passage of the spray through said opening.

35. A machine of the class described having, in combination, a blacking receptacle, a downwardly sloping rim arranged to pro- 130

vide a restricted opening in the top of said receptacle, and means for delivering a spray of blacking toward said opening, the receptacle having a lateral relief outlet from below said rim to facilitate the passage of the spray through said opening.

36. A machine of the class described having, in combination, a blacking receptacle formed with an opening, means for delivering a spray of blacking toward said opening, and additional means for creating an inward current through said opening to facilitate the passage of the spray through the opening.

37. A machine of the class described having, in combination, a blacking receptacle formed with an opening in its top and with an outlet above the body of the blacking, means for delivering a spray of blacking toward said opening, a conduit communicating with said outlet, and means for creating an outward current in said conduit to facilitate the passage of the spray through said opening.

38. A machine of the class described having, in combination, a blacking receptacle formed with an opening in its top and with an outlet above the body of the blacking, means for delivering a spray of blacking toward said opening, a conduit communicating with said outlet, and means for delivering a jet of air into said conduit to induce an outward current through said outlet.

39. A machine of the class described having, in combination, a blacking receptacle formed with an opening in its top and with an outlet above the body of the blacking, a compressed air reservoir, means for utilizing air from said reservoir to draw blacking from the receptacle and deliver it in the form of spray toward said opening, a conduit communicating with the outlet from said receptacle, and means for delivering a jet of air from the air reservoir into said conduit to induce an outward current through said outlet.

40. In a machine of the class described, mechanism for delivering blacking in the form of spray, and means for positioning the work relatively to said mechanism, said means operating also to limit the field of operation of the spraying mechanism by confining the spray to a predetermined marginal portion of the work.

41. In a machine of the class described, mechanism for delivering blacking in the form of spray, and means for determining adjustably the distance of the work from the point of delivery of the spray, said mechanism and means being constructed and arranged to limit the application of blacking to a marginal portion of the work.

42. In a machine in which the work is presented by hand to relatively stationary mechanism for delivering blacking in the form of spray, the combination with said mechanism of means for enabling an operative to hold and move the work so as to confine the spray to a predetermined marginal portion thereof.

43. In a machine of the class described, mechanism for delivering blacking in the form of spray, and a member operative as a shield to prevent the spray from striking the work beyond a predetermined marginal line, said member operative also as a gage to determine the distance of the work from the point of delivery of the spray.

44. In a machine of the class described designed for the purpose of blacking the marginal portion of the upper surface of a piece of work, the combination with mechanism for delivering blacking in the form of spray, of gaging means for positioning the work at the proper distance from the point of delivery of the spray and with a predetermined marginal portion thereof exposed to the spray, and a shield for preventing the application of spray beyond said marginal portion of the work.

45. In a machine of the class described designed for the purpose of blacking the marginal portion of the upper surface of a piece of work, the combination with mechanism for delivering blacking in the form of spray, of a shield and gaging means cooperating to position the work and to control the spray so that only a predetermined marginal portion of the work receives the blacking.

46. In a machine of the class described, the combination with means for spraying blacking upon the work, of means for positioning the work constructed and arranged to insure that only a predetermined marginal portion thereof will be sprayed.

47. A machine of the class described having, in combination, means for delivering blacking in the form of spray, and means at one side of the path of said spray having a surface for preventing lateral deflection of the spray and having another surface for determining the distance of the work from the point of delivery of the spray.

48. In a machine in which the work is presented by hand to relatively stationary mechanism for delivering blacking in the form of spray, the combination with said mechanism of means to confine the spray to a predetermined marginal portion of the work.

In testimony whereof I have signed my name to this specification.

FREDERICK M. FURBER.
